CLAIM

We claim the ornamental design for a syringe grip, as shown and described.

DESCRIPTION

FIG. 1 is a front, top, right perspective view of a syringe grip according to the claimed design;

FIG. 2 is a rear, bottom, left perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The ornamental design which is claimed is shown in solid lines in the drawings. The broken lines of equal length dashes in the drawings depict portions of the syringe grip that form no part of the claimed design.
